(57) CLAIM

The ornamental design for a post-surgery liposuction garment, as shown and described.

DESCRIPTION

FIG. 1 is a front view of a post-surgery liposuction garment with a snapped crotch and closed back showing my new design;

FIG. 2 is a left side view of the post-surgery liposuction garment with a snapped crotch and closed back;

FIG. 3 is a rear view of the post-surgery liposuction garment with a snapped crotch and closed back;

FIG. 4 is a right side view of the post-surgery liposuction garment with a snapped crotch and closed back;

FIG. 5 is a front view of the post-surgery liposuction garment with an unsnapped crotch;

FIG. 6 is a left side view of the post-surgery liposuction garment with an unsnapped crotch and open back with foam insert removed;

FIG. 7 is a right side view of the post-surgery liposuction garment with an unsnapped crotch and open back with foam insert removed;

FIG. 8 is a rear view of the post-surgery liposuction garment with an unsnapped crotch and open back with foam insert removed; and,

FIG. 9 is a front view of the post-surgery liposuction garment as worn.

Top views and bottom views are not included and any portion not shown forms no part of the claimed design. The broken lines in FIG. 9 show environment and form no part of the claimed design. The broken lines illustrating stitching in FIGS. 1-9 show portions of the garment that form part of the claimed design.

1 Claim, 6 Drawing Sheets
